ICE BAG

Original Filed Nov. 5, 1929

INVENTOR.

FIG. III. FIG. IV.

BY G. E. ROUX
Victor J. Evans
ATTORNEY

UNITED STATES PATENT OFFICE

GRACE E. ROUX, OF HANFORD, CALIFORNIA

ICE BAG

Application filed November 5, 1929, Serial No. 405,039. Renewed April 11, 1932.

This invention relates to improvements in ice bags and has particular reference to an ice bag to be applied to the head in the form of a cap.

5 Another object of the invention is to produce an ice bag which will not fall from the head upon every slight movement as is common fault with the ordinary type of ice bag.

A further object is to produce a device 10 which will cover a larger area of the head than the usual ice bag.

A still further object is to produce a device which may be so adjusted to the head that the wearer may lie down comfortably in any 15 position.

Other objects and advantages will be apparent during the course of the following description.

In the accompanying drawing forming a 20 part of this specification and in which like numerals are employed to designate like parts throughout the same,

Figure I is a top plan view of my bag as the same appears before being filled and applied to the head,

Figure II is a cross section taken on the line 2—2 of Figure I,

Figure III is a side elevation of my bag as the same appears when applied to the head, 30 and

Figure IV is a view similar to Figure I with the bag given a quarter of a degree turn.

Ice bags are in common use for applying ice to various parts of the body. These ice 35 bags are usually purse shaped, into which a quantity of ice is placed. Due to their shape they cannot be effectively placed upon the head without falling therefrom through a slight movement of the head or through the 40 changing of the position of the ice in the bag due to melting.

Applicant has therefore produced an ice bag which may be used as a flat ice bag or may be formed and tied in such a manner 45 that it will fit the contour of the head and due to the peculiar arrangement of the ice holding receptacle the cooling medium may be brought into contact with, for instance the front and back of the head as well as one side thus allowing the wearer to lie down in

comfort on the side which is unincumbering by the ice compartment or the bag can be so moved upon the head that the ice will extend from side to side of the head and over the forehead thus leaving the back of the head 55 unincumbered and capable of being brought comfortably into engagement with a head support such as a pillow or back of a chair.

In the accompanying drawing wherein for the purpose of illustration is shown a preferred embodiment of my invention, the numeral 5 designates a circular blank having a plurality of eyelets 6 spaced at predetermined positions and at points adjacent the edge of the blank. Secured to this blank as 60 by stitching, cementing or any other suitable manner, is an ice receptacle preferably formed of a flexible impervious material 7. This receptacle has secured thereto a ring 8 to which is threaded a cap 9. By viewing Figure I it will be noted that the receptacle 7 extends to each side as shown at 11 and 12 and to the front as shown at 13, thus forming substantially a T-shaped receptacle into which the ice may be placed.

Assuming now that the receptacle has been filled with ice, the blank and the receptacle forming a unit may now be placed upon the body in a flat condition or may be placed upon the head as for instance in the position 80 shown in Figure III. When placed upon the head a tie cord 14 is employed to extend between one group of eyelets and the next adjacent group thus forming the blank into a cap and as soon as proper adjustment has been made the tie cord is knotted so as to hold the adjusted parts in position. It is of course understood that tie cords are used 85 on the opposite side of the bag.

When the bag is used as shown in Figure III it will be noted that the ice receptacle is so positioned that the ends 11 and 12 extend over each side of the head while the portion 13 extends over the forehead. In this 95 position the patient can comfortably lie down or lean back against a head rest without the danger of the bag falling off and with perfect comfort. Should the bag be positioned as shown in Figure IV the patient can 100

lie down upon his right side without inconvenience.

It will thus be seen that I have produced an ice bag which will perform all of the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I

claim:—

1. In a device of the character described, a flat circular blank, a series of eyelets positioned about said blank and adjacent the margins thereof, a receptacle secured to said blank, said receptacle having extensions approaching the margin of said blank at the top and bottom and one side thereof, and cords engaging said eyelets so that said blank assumes the shape of a cap for head wear.

2. In a device of the character described, a flat circular blank, a receptacle secured to said blank at a point adjacent a portion of the margin of said blank, said receptacle having extensions projecting laterally therefrom to a point adjacent other portions of the margin of said blank and secured thereto, eyelets secured to said blank in groups, said groups being spaced 90° apart with reference to the circumference of said blank, and cords extending thru said eyelets so that said blank assumes the shape of a cap for head wear.

In testimony whereof I affix my signature.

GRACE E. ROUX.
